STORM SHUTTER

Edward W. Reiber, Miami, Fla.

Application August 28, 1936, Serial No. 98,397

3 Claims. (Cl. 189—55)

This invention relates to a combined shutter and awning structure designed for use in protecting the windows and doors of buildings.

The primary object of the invention is to provide a device of this character which may be moved to a sloping position providing an awning, or extended to a position within the frame of the closure with which the device is used, to protect the closure against hurricanes or violent storms, or for general protection of the building while the building is unoccupied.

An important object of the invention is to provide a device of this character including an operating means of a construction to permit the device to be readily and easily adjusted for use either as an awning or shutter.

A still further object of the invention is the provision of a device which may be moved to a position to only partially close the window or door frame with which the device is used, insuring proper ventilation, the operating mechanism holding the device in its positions of adjustment.

Referring to the drawings:

Figure 1 is an elevational view of a combined awning and shutter, a portion of the device having been broken away illustrating the operating mechanism.

Figure 2 is a sectional view taken on line 2—2 of Figure 1.

Figure 3 is an enlarged sectional view taken on line 3—3 of Figure 1.

Figure 4 is an enlarged sectional view taken on line 4—4 of Figure 2.

Figure 5 is a transverse sectional view taken on line 5—5 of Figure 1.

Figure 6 is a sectional view taken on line 6—6 of Figure 2.

Figure 7 is a side elevational view illustrating a modified form of the invention, designed for use with casement windows.

Figure 8 is a sectional view taken on line 8—8 of Figure 7.

Figure 9 is a detailed view illustrating a spring which operates to urge the device outwardly when the device is moved to provide an awning.

Referring to the drawings in detail:

The frame of a window is indicated generally by the reference character 5 and as shown, is provided with brackets 6 which are secured to the frame near the upper end of the window.

These brackets provide a support for the rod 7 which in turn provides the support for the combined awning and shutter. The combined awning and shutter comprises a body portion 55 constructed preferably of sheet metal and in-

cludes an outer member 8 and an inner member 9, the outer and inner members being connected by means of the end pieces 10 which are formed with offset portions 11 providing guideways for the bars 12 which form a part of the adjustable section 13 of the body portion.

This adjustable section 13 is designed to slide out of the body portion when the device is moved to a vertical position, or to a position providing a shutter to completely close the window. Connected with the adjustable section 13 are pivoted arms 14 which have their inner ends connected to the operating shaft 15 which is secured to the window frame, and mounted in brackets 16.

One of the brackets 16 is provided with bearings in which the shaft 17 operates, the shaft 17 being provided with a crank handle 18, by means of which the shaft 17 may be rotated.

Mounted on one end of the shaft 17 is a worm 19 that meshes with the gear 20 which is secured to the shaft 17 so that when the shaft 17 is rotated, the rotary movement will be imparted to the shaft 15 moving the arms 14 to operate the adjustable section 13. The reference character 21 designates the bracket to which the arms 22 are connected, there being provided springs 23 on the bracket, which springs urge the arms 22 upwardly towards the shaft 17. Cables 24 are connected with the free ends of the arms 22, which cables also connect with the adjustable section 13, as shown by Figure 1. Thus it will be seen that when the body portion is moved to a position as shown by Figure 1 of the drawings, the springs will be placed under tension, and will return the arms 22 to their normal positions, as the body portion swings upwardly to provide an awning, thereby retracting the adjustable section 13, moving the adjustable section 13 to the position shown by Figure 2, providing an awning. When the crank handle 18 is operated in the reverse direction the arms 14 will swing downwardly extending the adjustable section 13 to a position to completely close the window frame.

In order that the device may be operated with the minimum amount of exertion on the part of the operator, coiled springs 25 are provided, and are connected with the body portion, the opposite ends of the coil springs 25 being anchored to the brackets 6 with the result that as the body portion swings downwardly these springs 25 will be placed under tension, to urge the body portion upwardly when the crank handle is operated to swing the body portion to its upper-most position.

In the modified form of the invention as shown by Figure 7 of the drawings the body portion 55

includes an upper section 26 and a lower section 27, the sections being pivotally connected at 28, so that the section 27 will be supported in such spaced relation with respect to the window frame, 5 that the device may be used with casement windows such as shown at 29 in Figure 7 of the drawings.

From the foregoing it will be seen that due to the construction shown and described, I have provided a device which may be used to provide an awning for a window or door, and that by moving an operating mechanism, the device may be moved to a position providing a shutter to completely close the opening, protecting the window 15 or door against hurricanes or violent storms.

Having thus described the invention, what is claimed is:

1. In a combined awning and window shutter, a hollow body portion, an adjustable shutter section slidably mounted within the body portion and adapted to extend beyond the end of the body portion, a pair of yieldable arms mounted within the body portion, cables connecting the arms to the adjustable shutter section, arms pivotally 20 connected to the movable shutter section, means for operating the arms whereby the body portion is moved from an inclined position providing an awning, to a position closing the window

frame, and said arms adapted to retract the adjustable shutter section when the body portion is moved to its inclined position.

2. In a combined awning and window shutter, a hollow body portion, means for pivotally connecting the upper end of the body portion to a window frame, a shutter section slidably mounted within the hollow body portion, a pair of pivoted arms mounted within the body portion, coiled springs for normally urging the arms in one direction, flexible members connecting the free ends of the arms to the shutter section and adapted to normally urge the shutter section to a position within the hollow body portion, and means for swinging the body portion on its pivot. 5

3. In a combined awning and window shutter, a hollow body portion, means for pivotally connecting the body portion to a window frame, said body portion having offset portions formed along its longitudinal side edges, providing guideways, 10 a shutter section, bars secured to the longitudinal side edges of the body portion and disposed in the guideways, slidably mounting the shutter section within the body portion, means for swinging the body portion on its pivot, and means for 15 restricting movement of the shutter section within the body portion.

EDWARD W. REIBER.
